UNITED STATES PATENT OFFICE.

LEWIS WILLIAM NOYES, OF EAST PEPPERELL, ASSIGNOR TO E. I. K. NOYES,
OF CAMBRIDGE, MASSACHUSETTS.

CARD-BOARD-MANUFACTURING MACHINE.

SPECIFICATION forming part of Letters Patent No. 374,848, dated December 13, 1887.

Application filed March 26, 1887. Serial No. 232,497. (No model.)

To all whom it may concern:

Be it known that I, LEWIS WILLIAM NOYES, of East Pepperell, in the county of Middlesex, of the Commonwealth of Massachusetts, have 5 invented a new and useful Improvement in Card-Board-Manufacturing Machines; and I do hereby declare the same to be described in the following specification, and represented in the accompanying drawings, of which—

10 Figure 1 is a longitudinal and vertical section of the principal parts of a machine embodying my invention, the nature of which is defined in the claims hereinafter presented. Fig. 2 is a section, on an enlarged scale, of the 15 brush-receptacle and its brushes, as hereinafter explained.

In Fig. 1 of such drawings, A is a vat for holding paste, it being formed as represented and provided near its bottom and through its 20 outer side with two slots or inducts, *a a*, opening into a narrow receptacle or chamber, B, arranged against such outer side and furnished in its outer side with two slots, *b b*, which are directly opposite the slots *a a*. In the chamber or receptacle B are three brushes, *c d*, and *e*, the middle one having bristles projecting in opposite directions from it toward those of the other two brushes, whose bristles extend toward the median brush. In the upper part 25 of the paste-vat is a pair of feed or draw rollers, C D, which in practice are to have mechanism for revolving them. There is also in the paste-vat at its rear portion, and above that part of it in which the mass, *f*, of liquid paste is situated, two guide-rollers, E and F. Furthermore, outside of and in front of the 30 vat are two pairs of guide-rollers, G and H and I and K, and in front of them are three beams or rollers, L, M, and N. There is also 35 such a beam or roller, O, in front of the upper feed-roller. In advance of the middle roller, M, is a take-up beam or roller, P. The roller P rests upon another roller, S', which 40 has mechanism for revolving it, in order for the roller P to take up the card-board. Each journal of the roller P extends into a vertical slot, *a'*, in the frame R.

The vat and the rollers, as above described, are supported in and by a frame, R.

50 The feed-rollers have their shafts connected

by gears, (shown in dotted lines at *s s*,) there being on one of the said shafts a pulley, *t*, about which an endless belt, *n*, passes to and around a motor-drum, *v*, about which and a pulley, *x*, on the shaft of the beam S' an endless belt, *w*, works. 55

Card-board as usually made is composed of three or more sheets of paper laid in pack and pasted together, the inner sheet or sheets being paper of a coarser quality than that of each of the outer sheets. If, now, we suppose there is wound on each beam L, M, N, and O a continuous strip or roll of paper, and that the sheet from the beam L is led to and under the guide-roller H, thence upward to and over the guide-roller G, thence to and partly around the lower feed-roller, D, and thence to the beam P, and we also suppose that each of the beams M and N is furnished with the coarser paper, and from such beams M and N such paper is led under and against the guide-rollers I and K, thence through the brush-chamber B and between its brushes, thence through the mass of paste, thence under and partly around the rollers E and F, thence between 70 the feed-rollers and to the take-up beam P; furthermore, if we suppose the sheet of paper from the roller O to be led to the upper part of the upper feed-roller and thence between 75 the feed-rollers, also that the said feed-rollers and the beam P are put in revolution in the directions as shown by arrows on them, the two sheets R' and S from the rollers M and N will be drawn through the paste and 80 covered on each of their sides therewith, and in passing between the feed-rollers such sheets will be pressed into close contact with each other and with the sheets T and V of the rollers O and L, and all four of the sheets pasted together will be wound upon the beam P. So, 85 if desirable, but one of the sheets R and S may be run through the paste and between and cemented to the sheets T and V, in which case but one of the beams M N and two of the four guide-rollers E F and I K need be used. 90

The brush-chamber and its brushes constitute an important element or feature of my invention, as they serve to form close inducts for the sheets to pass into the vat and to prevent the escape of paste therefrom. 95

I claim—

1. The combination of the paste-vat A and the chamber B and the brushes thereof, with the feed or draw rollers C D, the guide-rollers E F G H I K, and the beams L, M, N, O, and P, such feed-rollers and the beam P being provided with mechanism for revolving them, and all being arranged substantially and to operate in manner and for the purpose as set forth.

2. The combination of the paste-vat A, the

chamber B, and brushes therein, with the feed or draw rollers C D, guide-rollers F G H I, and the beams L, M, O, and P, such feed or draw rollers and the beam P being provided with mechanism for revolving them, and all being arranged substantially and to operate in manner and for the purpose as set forth. 15

LEWIS WILLIAM NOYES.
